UNITED STATES PATENT OFFICE.

CHESTER B. ALBREE, OF PITTSBURGH, PENNSYLVANIA.

GRATING.

1,158,154.

Specification of Letters Patent.

Patented Oct. 26, 1915.

Application filed February 13, 1914. Serial No. 818,490.

To all whom it may concern:

Be it known that I, CHESTER B. ALBREE, a citizen of the United States of America, and a resident of Pittsburgh, Allegheny county, Pennsylvania, have invented a new and useful Improvement in Gratings, of which the following is a full, clear, and exact description, reference being had to the accompanying drawings, forming part of this specification, in which—

Figure 1 is a perspective plan view showing one form of my invention: Fig. 2 is a detail of Fig. 1 before upsetting; and Fig. 3 is a sectional side elevation showing a modified form.

My invention relates to gratings, and is especially designed for covering ventilating openings in streets, although it may be used for window gratings, floor gratings, window sashes, registers, or in any other location where gratings are used.

The object of the invention is to cheapen and improve these grating structures, and greatly reduce the amount of labor incident to their manufacture.

In the drawings, referring to the forms shown in Figs. 1 and 2, 2, 2 represent longitudinal girder bars of considerable depth relative to the other cross bars 3, 3, which are secured thereto to form the grating. These deeper girder bars 2 are slotted inwardly from one edge at any desirable distances; this slotting being carried out by punching, as this is much cheaper than milling or other methods of forming slots. The shallower bars 3 which cross the deeper bars may or may not be slotted at the points where they cross the deeper bars. I prefer, however, to slot them by the punching method, since thereby they will act to space apart the longer bars at the desired distances and make a somewhat stronger structure.

The slots 4 in the deeper bars may be undercut by giving them a dovetail form, or they may be made with parallel sides, as in Fig. 3. The depth of these slots in the deeper bars is slightly less than the depth of the unslotted portions of the shallower bars, so that when the bars are assembled by inserting the shallower bars whether notched or not in the slots of the deeper bars, the shallower bars will project above the deeper bars a slight distance, say one-sixteenth of an inch for ordinary sized grating material, as shown in Fig. 2. The shallower bars are

then upset within the slots of the deeper bars, preferably by hydraulic press, which has a device of sufficient length to act upon each juncture of a shallower bar with the deeper bars. This will, of course, depend upon the particular size of sections desired, and the upsetting operation may take place step by step, or otherwise if desired. During this upsetting operation, the portions of the shallower bars which project above the deeper bars disappear and the upper edges of the bars are substantially flush with each other, the metal of the cross bars being upset to fill the recesses in the girder bars and the girder bars being forced into the cross bars, thereby locking the bars together.

While I prefer to undercut or dovetail the slots in the deeper bars, yet they may have parallel sides, as I find that the upsetting operation will act to sufficiently clinch or secure the parts together.

In Fig. 3, I show a form where the cross bars 3^a are unslotted. In this case a grid may be used for aiding the operator in locating the deeper bars 2^a during assembling and pressing. The upsetting operation is preferably carried out while the metal is cold.

The advantages of my invention will be obvious to those skilled in the art, since the making of these gratings has heretofore been a matter involving a large amount of skilled labor, riveting operations, special bending of strips in zigzag form, etc. All of these intermediate operations are done away with by my invention, as all that is necessary is to slot one or both sets of bars prior to the upsetting operation. A strong, well-braced and secured grating structure is thus afforded at comparatively low labor cost.

Owing to the upsetting operation, the receiving slots are substantially filled up with the upset metal, so that as these parts of the bars are in compression when under load and the slots are filled up with the upset metal, the bars are not weakened, and thus the weakening effect of the slotting is done away with. Furthermore, this upsetting operation brings the metal into such close contact that moisture does not enter and reach the freshly cut surface of the slot. Corrosion is thus avoided. The only exposed surfaces of the bars are the rolled surfaces having the usual scale thereon.

I claim:

1. The method of making gratings, con-

sisting in inserting within the slots of parallel girder bars a series of cross bars of such depth that the cross bars project above the girder bars when placed in position, and 5 then applying pressure to the bars, thus causing a lateral flow of the metal of the cross bars at the joints to fill the slots in the girder bars and lock said bars together; substantially as described.

10 2. A reticulated grating composed of a number of parallel spaced apart girder bars, each having spaced registering slots extending inwardly from one edge thereof, and a plurality of spaced apart cross bars having 5 slots extending in from one side registering with the slots in the girder bars, the girder bars being forced into the cross bars by compression, and the metal of the cross bars being spread and locked within the girder bar slots, substantially as described.

3. A reticulated grating composed of a number of parallel spaced apart girder bars, each having spaced registering slots extending inwardly from one edge thereof, and a

plurality of spaced apart cross bars resting 25 within the slots of the girder bars, the girder bars being forced into the cross bars by compression, and the metal of the cross bars being spread and locked within the girder bar slots; substantially as described. 30

4. A reticulated grating composed of a number of parallel spaced apart girder bars, each having spaced registering undercut slots extending inwardly from one edge thereof, and a plurality of spaced apart cross bars resting 35 within the undercut slots of the girder bars, the girder bars being forced into the cross bars by compression, and the metal of the cross bars being spread and locked within the undercut girder bar slots; 40 substantially as described.

In testimony whereof, I have hereunto set my hand.

CHESTER B. ALBREE.
